EDWARD K. SANDEMAN AND LAUNCELOT EDGAR CURRAH, OF ALDWYCHE, LONDON, ENGLAND, ASSIGNEES TO INTERNATIONAL STANDARD ELECTRIC CORPORATION, OF NEW YORK, N. Y., A CORPORATION OF DELAWARE

DOT INSERTION

Application filed February 26, 1931, Serial No. 518,370, and in Great Britain April 25, 1930.

This invention relates to electric telegraphy and more particularly to an improved method of dot insertion.

It is known to use, at the receiving station, 5 a mechanical relay which produces dots continually when no signal is being received and which stays in one of its stable positions when and as long as a signal impulse is being received. This results in the dots, which 10 either arrive greatly attenuated or are not transmitted at all, being filled in when necessary. By a dot is meant the shortest length of signal occurring.

With the advent of high speed telegraphy 15 and a consequently higher dot frequency it becomes increasingly difficult to make a mechanical relay which will respond to the frequency of the dots and furthermore it is undesirable to transmit the dot frequency 20 because of the frequency range required.

It is an object of this invention to provide a method of dot insertion in which the above defects are largely avoided.

It is a feature of this invention that dot 25 insertion is accomplished by means of mechanically static apparatus. By this is meant apparatus which has no moving parts and is consequently free from the undesirable effects of inertia and momentum.

30 It is a further feature of the invention that thermionic valves are employed for the purpose of inserting the dots in a received signal.

According to another feature of the invention, by means of an apparatus termed a 35 squaring device the dots are inserted and both the dots and the signal impulses are squared. Other features will be apparent from the following description.

The invention will now be described with 40 reference to the accompanying drawings of which Fig. 1 is a diagram illustrating the principle of dot insertion.

Fig. 2 shows the circuit arrangement of one form of the invention.

45 Fig. 3 illustrates another method of carrying out the invention.

Fig. 4 illustrates a squaring device suitable for use in connection with the invention.

Two embodiments of the invention will be 50 described by way of example.

Referring now to Fig. 1, time is plotted horizontally and amplitude (after magnification) is plotted vertically. At (P) is shown the type of current which would occur with a code in which, in each of a number of successive contiguous intervals of time, current is either applied or not applied to the line. These periods of time are numbered 1, 2, 3, 4, 5 etc. The amplitude of the current pulse is shown as $+A$ and it is evident that, 55 by adding to this current a steady direct current of amplitude $-1/2A$ a current of the form shown at (Q) will be obtained. This represents a typical current or voltage supplied at the transmitting end of the line. It 60 is possible, of course, that this may be modified considerably by the apparatus at the transmitting end as well as by the attenuation and phase distortion of the cable. Owing 65 to the fact that the cable cannot transmit 70 the dot frequency, the current pulses shown at (Q) will be suppressed during the time intervals 1, 2, 3, 4, 5, 6 and 14 and 15. Owing 75 to the distortion of the cable the current pulses at the intervals 7, 8, 9, 10, 11, 12 and 13 will arrive at the receiving end in some 80 such form as is shown at (R). By suitable shaping means these signals can be restored to their original form as shown at (S) and it is evidently necessary in order to obtain 85 the original signal as shown at (Q) that the dots be added in the intervals 1, 2, 3, 4, 5, 6 and 14 and 15.

It is assumed that some means of synchronism between the transmitting and receiving 90 ends is available. For simplicity and by way of example, it will be considered that synchronism is obtained by transmitting a very low frequency wave on a carrier above the telegraph range, this low frequency wave 95 being a sub-multiple of the dot frequency. By frequency multiplication it is therefore possible to obtain a current wave of the same frequency as and in exact synchronism with the dot frequency. The dot frequency is 95 here assumed to be an alternating wave at the receiving end whose half period is exactly equal to one of the time intervals 1, 2, 3, 4, 5, 6 etc. of Fig. 1.

Referring to Fig. 2 which represents the 100

receiving end of a transmission system, such, for example, as a submarine cable, (A+E+PC) represents the necessary amplifier, equalizers and phase compensation gear to restore the signals to their original form as far as such means is capable of so doing. (SD1) is an arrangement for making a signal square, that is, for restoring signals as at (R) to the form as at (S) (see Fig. 1).
 10 The separating amplifier (SA) transmits the signals received from SD1 to the receiving apparatus (R). The receiving apparatus, for example, may consist of a thermionic valve distributor supplying any required 15 number of channels. The high pass filter (HPF) selects the carrier wave and supplies it to a demodulator (DM). The output of the demodulator (DM) supplies a synchronizing wave to the variable phase shifter (PS) the output of the phase shifter feeds into the frequency multiplier (FM) which supplies the dot frequency to the squaring device (SD2). This squaring device (SD2) supplies the dot frequency having the form 20 as at (T) in Fig. 1 to the push pull amplifier (PPA) which in turn supplies the dot frequency to the receiving apparatus (R) in parallel with signals supplied from the cable through the separating amplifier (SA). The 25 paralyzing detector (PD) when it receives any signal from the cable paralyzes the amplifier (PPA) and prevents the dot frequency from being supplied to (R). The low pass filter (LPF) selects telegraph frequencies 30 and rejects the wave carrying the synchronizing frequency.

Except for the detailed operation of the pieces of apparatus (PD) and (PPA) which is explained immediately below, the operation 40 of the circuit is now clear and it is evident that a wave received in the form (R) will give rise to a wave as at (Q): Considering now the paralyzing device (PD), telegraph signals arriving from the cable 45 are applied to the resistance (1) whose midpoint is tapped through a suitable bias battery (2) to the common point of the filaments of valves (3) and (4). In this way any input voltage arriving at terminals (13) 50 is applied differentially to the grids of the valves (3) and (4) so that when one grid is increased positively by a certain amount the other is increased negatively by an equal amount.

55 The battery (5) is arranged to supply current to the plates of both the valves (3) and (4) in parallel, through the resistance (6).

The battery (2) is arranged to bias both 60 valves (3) and (4) so that normally in the absence of signals received from the cable substantially no current flows through the resistance (6). The bias is also so arranged that on the application of voltages across the terminals (13) of the magnitude of those 65 received from (SD1) an appreciable current

flows through the resistance (6). It will be noted that the direction of this current through the resistance (6) is quite independent of the polarity of the voltages supplied to terminals (13) since such voltages always increase the negative bias on one valve (so having no effect on the total current since this is already substantially zero) and decrease the negative bias on the other valve allowing a current of the necessary amplitude to flow. This current flowing through resistance (6) causes a potential drop to occur between its ends. It will be noted that resistance (6) is situated in the grid circuit 70 of amplifier (PPA).
 75

The midpoint of input resistance (7) is connected to one end of resistance (6) and the other end of resistance (6) is connected to battery (8) which is arranged to bias the amplifier for normal operation when the potential across resistance (6) is zero. Battery (11) supplies plate current to the plates of valves (9) and (10) through resistance (12). The plates of the two valves are directly connected to the receiver (R) in the manner 80 shown. It is evident from the above that (PPA) operates as a normal push pull amplifier. Further any changes in grid bias due to variations in current through resistance (6) do not cause any variations in potential between the ends of resistance (12) 85 so that when the amplifier (PPA) is paralyzed by paralyzing detector (PD) no effect appears in the output other than the cessation of the dot signals.

90 According to another embodiment of the invention the circuit arrangement of Fig. 3 is employed. This will be seen to comprise amplifiers, equalizers, phase compensators, separating filters, demodulator, phase shifter and frequency multiplier as in the previous case, like reference characters denoting like apparatus. In addition there is provided a squaring device (SD) of the type illustrated in Fig. 4, which shows a circuit arrangement comprising two thermionic valves. It will be seen that the connections 95 are symmetrical. The valves (1) and (2) have resistances (14) and (24) in their respective plate circuits (13), (14), (4), (12) and (23), (24), (4), (22). The grid circuit of valve (1) comprises grid (11), resistance (17), voltage source (26), part of resistance (24) extending from contact (25) to source (4) and thence to cathode (12). Valve (2) has a similar grid circuit symmetrical with respect to that of valve (1) and extending from grid (21) through resistance (27), source (16), contact (15), part of resistance (14) and source (4) to cathode (22).

100 Consider now that initially there is a relatively large plate current flowing through resistance (14) and a relatively small current through resistance (24). Assume that sources (16) and (26) were initially adjusted so that

in the absence of plate current through either valve the potentials on the grids would be equal to the value required to make the valves operate as normal amplifiers. In this condition with plate current through resistance (14), grid (21) is made negative with regard to its normal operating condition as an amplifier by an amount equal to the voltage drop in that part of resistance (14), included between (15) and (4). If this drop in potential of grid (21) is sufficient to effectively prevent any plate current flowing through resistance (24), then grid (11) is biased in its normal condition as an amplifier and a stable condition results. The system will remain in this condition until something happens to disturb it. Imagine now that a current flows through resistance (17) of such magnitude and in such direction as to momentarily bias grid (11) to such a value that the plate current in resistance (14) falls effectively to zero. The immediate result is that grid (21) assumes its normal bias, plate current flows through resistance (24) so that tapping (25) and consequently grid (11) are decreased in potential by the fall in volts along resistance (24) between battery (4) and tapping point (25). In this way valve (1) is held in a stable condition with no plate current and valve (2) in a stable condition with a normal plate current, the exact reverse of the stable condition obtained before the impulse was applied to grid (17). Application of a voltage to resistance (27) such as to make grid (21) sufficiently negative for a short period of time would set up the first condition again. It is evident that the amount of negative bias applied to each grid by plate current flowing through the other valve depends on the position of the tappings and therefore the position of the tappings controls the magnitude of the received impulse which must arrive before the opposite condition can be set up.

Referring now to Fig. 3, it will be seen that the squaring device will be kept continually supplied with dots from the frequency multiplier (FM) and the voltage of the dots may be applied to the squaring device across resistance (17).

In the absence of signals the dots will be squared and passed to the receiver (R). On arrival of signals which may be applied (in the correct phase) to resistance (27) the squaring device will remain in one of its stable positions while the signal persists, the dots being therefore suppressed. It is of course necessary to ensure that the amplitude of the signal voltage applied to the squaring device is sufficiently large, compared with the dot voltage, that the latter is unable to operate the device while the signal persists. In other words the squaring device should be effectively paralyzed by the signal. Although the amplitude of the input signal is made larger than that of the dot input, the amplitudes will be

the same in the output (which may be taken across resistance 24) because the squaring device always "flops" over to a constant limiting value.

What is claimed is:

1. A telegraph system comprising a receiving device, mechanically static apparatus adapted to supply dot impulses, a signal squaring device to which is applied the received signal and said dot impulses, and wherein said squaring device is adapted to supply said dot impulses to the receiving device during non-signalling periods and shaped signals complete with inserted dot impulses during signalling periods.

2. A telegraph system comprising a transmitting station, a receiving station, means for synchronizing the operation of devices at said stations comprising a current of predetermined frequency, mechanically static apparatus at said receiving station adapted to supply dot impulses to a receiving device and means whereby the said dot impulses are derived from the synchronizing current.

3. A telegraph system comprising a receiving device, mechanically static means for supplying continuously dot impulses to said device during non-signaling periods and means adapted to shape the received signals upon their arrival and before they are impressed on said receiving device.

4. A telegraph system comprising a thermionic valve device adapted to supply continuously to the receiver dot impulses derived from a synchronizing current and means for shaping said dot impulses before they are impressed on said receiver.

5. A telegraph system comprising a mechanically static apparatus adapted to supply continuously to the receiver dot impulses derived from a synchronizing current, means operated by an incoming signal to paralyze said mechanically static apparatus to suppress the supply of dots and a signal shaping device adapted to shape said dot impulses and said signals before they are impressed on said receiver.

In witness whereof we hereunto subscribe our names this 28 day of January, 1931.

EDWARD K. SANDEMAN.
